UNITED STATES PATENT OFFICE.

EDWARD E. WILSON, OF CLEVELAND, OHIO, ASSIGNOR TO KATHERINE L. SMOOTZ, OF CLEVELAND, OHIO.

SIDESTICK AND GALLEY LOCK.

1,123,154.

Specification of Letters Patent. Patented Dec. 29, 1914.

Application filed January 24, 1914. Serial No. 314,173.

To all whom it may concern:

Be it known that I, EDWARD E. WILSON, a citizen of the United States, residing at Cleveland, in the county of Cuyahoga and State of Ohio, have invented some certain new and useful Improvements in Sidestick and Galley Locks; and I do hereby declare the following to be a full, clear, and exact description of the invention, such as will enable others skilled in the art to which it pertains to make and use the same.

This invention relates to improvements in printers' galleys and has special reference to the side sticks and type lock construction.

The object of my invention is to provide a sheet metal side stick either tapered or of straight edge, which is adapted to receive and retain a sheet metal lock block at any predetermined point along the edge of said side stick.

The invention consists of a sheet metal side stick bent upon itself so as to provide a corrugated strip of metal interior of said side stick and leaving the outer surface of said side stick perfectly smooth.

My invention further consists in providing a sheet metal lock block provided with a corrugated tongue which is adapted to engage the corrugated strip interior of the side stick at any predetermined point along the edge of the same.

My invention still further consists in providing a means for locking the side stick to the rim of the galley when so desired.

The invention further consists of parts and combination of parts all of which will be hereinafter fully set forth and claimed.

In the drawings, Figure I, is a perspective view showing a galley with the type set therein illustrating the manner of employing my invention. Fig. II, is a perspective view showing the construction of the lock block. Fig. III, is a view of the side stick used in connection with my invention. This view is shown with parts broken away for the purpose of showing the interior arrangement. Fig. IV, is a sectional view taken through the end of the side stick and through the side of the lock block. Fig. V, is a plan view of a section of metal showing the manner of folding the same to form the side stick. Fig. VI, is a perspective view of one end of a side stick and a section of the galley rim showing the manner of holding the side stick to the galley rim

when such a connection is desired. Fig. VII, is a sectional view taken through lines A—A of Fig. VI, and Fig. VIII, is a plan view of the connecting member shown in Figs. VI, and VII, this view showing the connecting member inverted for the purpose of clearness.

This invention is adapted for several uses in the printers' trade but for the purpose of illustration I have shown the same as being employed in the following manner: A galley 1, is employed in which single type or "linotype" are set. After the type 2 have been set a tapered side stick 3 of any style is employed and placed next to one of the inner edges of the rim 1'. A correspondingly tapered side stick 4 constructed according to my invention is placed between the type and the side stick 3. By referring to Fig. V, it will be seen that the side stick 4 is formed of a blank sheet of metal having one edge corrugated as at 6; the metal is bent upward at each of the dotted lines thus forming the sections 7, 8, 9, 10 and 11. The corrugated portion 6 being bent so as to be entirely within the tubular side stick. (See Figs. III, IV and VII.) The section 11 terminating a short distance from the section 7 forms a slot 12 the whole length of the side stick. The lock block 13 is formed of any suitable material having a corrugated tongue 14. I prefer to construct this lock block 13 of sheet metal and have shown the same as being constructed in this manner. The upper inner edge 15 is formed so as to come a short distance from the edge of the side stick 4, (see Fig. IV). After the desired amount of type is set within the frame the lock block 13 is placed adjacent the side stick 4 with the tongue 14 inserted through the slot 12 of the side stick 4. The block is tilted so that the edge 16 is higher than the top edge of the side stick 4 thus throwing the tongue 14 out of engagement with the corrugated portion 6. The block is thus slid along the side stick 4 till the type is firmly supported and then the lock block 13 is dropped into position and the tongue 14 engages the corrugations of the section 6 thus preventing the type from falling, sliding or tipping. When it is desired to support a line of type longer than the ordinary lock block 13, two side sticks, such as 4', 4'', are employed and a lock block 13 is secured to each of these strips. A pin or

other lug 17 is provided on each of the lock blocks 13, 13 and a bar 18 provided with a series of orifices 19, 19, is secured to the lock blocks 13, 13 by means of the aforementioned 5 lugs 17 and orifices 19. By providing a plurality of orifices 19, 19 any desired length of type may be supported. In employing this side stick for various uses it becomes necessary at times that the side stick 4 be 10 connected with the rim 1' and for this purpose I have provided a connecting medium 20 provided on one end with a flange 21 which is adapted to engage the rim 1'. The opposite end of said connecting medium 20 is provided with a corrugated tongue 22 and a spring 23. The side stick 4 is provided with a slot 24 through which passes the tongue 22, the tongue 22 engaging the corrugated section 6 of the side stick in any predetermined location within the limits of the slot 24. By referring to Fig. VII it will be seen that by pressing the section 20 downwardly the tongue 22 will be disengaged from the corrugated section 6 and the connecting medium may be adjusted or removed. The shoulder 25 at the upper end of the tongue 22 engages the edge of the slot 24 thus when the spring 23 forces the tongue 22 into contact with the corrugated section 6 the member 20 is prevented from being lifted out of position until the member 20 is pressed downward as hereinabove 25 mentioned.

From the above description taken in connection with the drawings it will be clearly seen that I have produced a novel device for use in connection with the printer's trade. By constructing the side stick 4 in the manner according to my invention I have provided a smooth outer surface, which is absolutely necessary, and have at the same time provided a positive adjustable locking block for keeping the type from falling down, tilting or sliding.

It is obvious that the side stick may be cast instead of being made up of sheet metal and it is also obvious that many details of construction may be modified and still the objects of this invention be retained.

What I claim is:

1. A side stick of the type set forth comprising a sheet metal blank bent upon itself so as to form a tubular stick provided with a corrugated section interior of said stick, in combination with a block located at right angles to and slidably mounted exterior of said stick, said block provided with a corrugated tongue adapted to engage said corrugated section of said stick.

2. A side stick of the type set forth comprising a tubular stick provided with a corrugated section extending the whole length of said stick in combination with a block

located at right angles to and slidably mounted exterior of said stick, said block provided with corrugations adapted to engage the corrugated section of said stick.

3. A side stick of the type set forth comprising a tubular stick provided with a corrugated section interiorly located within 70 said stick and extending the whole length of said stick in combination with a block located at right angles to and slidably mounted exterior of said stick, said block having a corrugated section adapted to engage 75 corrugated section of said stick.

4. A side stick of the type set forth comprising a tubular stick provided with a corrugated section interiorly located within 80 said stick, a slot adjacent said corrugated section, in combination with a block located at right angles to and slidably mounted exterior of said stick, said block having a corrugated tongue adapted to enter said slot 85 of said side stick and engage with the corrugated section within said stick, all substantially as and for the purpose set forth.

5. A side stick of the type set forth comprising a tubular stick provided with a corrugated or toothed section located within 90 said stick, an arm slidably mounted on and extending from one side of said stick, said arm provided with a tongue adapted to engage with and be retained by said corrugated or toothed section of said stick.

6. A side stick of the type set forth comprising a tubular stick provided with a corrugated section interiorly located within 100 said stick, an elongated orifice located in the upper surface and at one end of said 105 stick, said orifice being adjacent the interior corrugations of said stick, in combination with locking means for locking the said stick to the rim of a printer's galley, said means consisting of a metallic strip having a flange at one end thereof and the opposite 110 end provided with a corrugated tongue, said tongue adapted to engage the corrugated section of the stick through the elongated slot and the flange adapted to engage the 115 rim frame of said galley, all substantially as and for the purpose set forth.

7. A side stick of the type set forth comprising a corrugated or toothed strip located within said stick, a block slidably mounted 115 at the side of said stick, said block provided with a toothed or corrugated tongue adapted to engage said corrugated or toothed strip of said stick.

Signed at Cleveland in the county of 120 Cuyahoga and State of Ohio this 29th day of December 1913.

EDWARD E. WILSON.
